UTILITY CONTROL, SUPPLY, AND SERVICE UNIT
FOR LABORATORY TABLES

Loyd A. Whitener, Jr., and Herman B. Carpenter,
Hickory, N.C., assignors to Southern Desk Company,
Hickory, N.C., a corporation of North Carolina

Filed Apr. 10, 1959, Ser. No. 55,435

Term of patent 14 years

(Cl. D16—2)

Figure 1 is a rear perspective view of a utility control, supply, and service unit for laboratory tables embodying our new design;

Figure 2 is a top plan view thereof on a reduced scale;

Figure 3 is an enlarged front elevational view thereof showing portions of the lamp shade broken away; and

Figure 4 is a right side elevational view thereof, as shown in Figure 3.

The dominant features of our design reside in those portions shown in full lines.

We claim:

The ornamental design for a utility control, supply, and service unit for laboratory tables, substantially as shown and described.
